United States Patent Office

Des. 190,546
Patented June 6, 1961

190,546

SPRINKLER

Russell B. Nelson, Peoria, and Robert K. Unter, Roscoe, Ill., assignors to L. R. Nelson Mfg. Co., Inc., Peoria,
Ill., a corporation of Illinois

Filed May 20, 1960, Ser. No. 60,666

Term of patent 14 years

(Cl. D91—1)

Fig. 1

Fig. 2

The dominant features of our new design are shown in solid lines.

We claim:

The ornamental design for a sprinkler, as shown and described,
